1,578,804

UNITED STATES PATENT OFFICE.

EDGAR P. COOK, OF GRANVILLE, OHIO.

AIR GUN.

Application filed April 23, 1924. Serial No. 708,329.

To all whom it may concern:

Be it known that I, EDGAR P. COOK, a citizen of the United States, and a resident of Granville, county of Licking, and State of Ohio, have invented a new and useful Improvement in Air Guns, of which the following is a specification, the principle of the invention being herein explained and the best mode in which I have contemplated applying that principle, so as to distinguish it from other inventions.

This invention relates to air guns. More particularly it comprises a device of that character having an improved and simplified construction rendering the same more effective in use and including mechanism for preventing the accidental release of the operated parts before the spring tensioning means has been restored to normal position.

The present construction to a certain extent resembles the apparatus shown in applicant's Patents No. 1,045,373 granted November 26, 1912, and No. 1,116,675, granted November 10, 1914. However, the various features thereof have been improved to insure more efficient operation, as well as to simplify the construction and increase the safety of handling the device. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

Fig. 1 is a side elevation of the air gun embodying this invention; Fig. 2 is a longitudinal section through the air gun shown in Fig. 1, showing the working parts on a slightly enlarged scale; Fig. 3 is an enlarged transverse sectional view taken along the line 3—3 shown in Fig. 2; Fig. 4 is a perspective view showing the movable air chamber used in the air gun; Fig. 5 is a side elevation of the automatic hammer-setting and locking slide; Fig. 6 is an end view of the slide shown in Fig. 5; Fig. 7 is a bottom plan view of the slide shown in Fig. 5; Fig. 8 is a side elevation of the preferred form of bullet to be used in this air gun; Fig. 9 is an enlarged longitudinal sectional view showing the operative parts of the air gun

with the spring setting mechanism moved to extreme rearward position; Fig. 10 is a view similar to Fig. 9 showing the spring setting mechanism just prior to its being moved to final closed position and with the safety slide still in position to prevent the accidental release of the hammer; and Fig. 11 is a view similar to Figs. 9 and 10, but showing the spring setting mechanism fully restored to normal position with the safety slide drawn forwardly so as not to interfere with the release of the hammer.

As is clearly shown in the drawing, the air gun comprises a stock or shoulder portion 1, a trigger guard 2 projecting from beneath the forward end of the same, a casing 3 mounted upon the forward end of the stock, and a barrel 4 screw-threadedly engaged in the forward end of the casing. The barrel is provided adjacent the rearward end of its bore with an enlarged recess within which the bullet or other missile may be seated prior to its discharge. The casing 3 is of substantially cylindrical cross section except at its rearward end and it is provided on its upper side adjacent its forward end with an opening 8 through which the bullet or missile may be placed within the recessed portion of the barrel. Within the casing 3 an air chamber 9 is adapted to slide. Said air chamber is of cylindrical form and is closed at its forward end 10, which is of heavier metal than the cylindrical portion and is provided on its forward face with a countersunk recess of a size to engage over the end of the barrel when said chamber is in its forward position. Said barrel end of the air chamber is provided with an aperture concentric with the countersunk portion on its forward face of the same diameter as the recessed portion of the barrel and in alignment with the bore thereof, said aperture being provided with an enlarged conical section adjacent its inner end.

As is clearly shown in Fig. 4, the cylindrical portion of the air chamber is provided with an extension arm 25 at its forward end and with a downwardly projecting lug 54 at its rearward end for purposes which will presently appear. Telescopically engaged within the air chamber there is provided a plunger 11 having a cylindrical casing forming the forward part of a telescopic spring housing 32. At the rearward end of said forward portion of the casing it is provided at each of its sides with lugs 18 adapted to

be engaged by pivotally mounted spring pressed sears 14 through their hook-shaped forward ends 17 when said plunger is at its rearward position within the air gun. A 5 spring 19, seated between the fixed rearward section of the spring housing and bottom plate 15 connecting the companion sears 14, serves to maintain the forward ends of the sears in position to engage the lugs on the forward section of the spring casing. The 10 rearward portion of the spring casing is slotted throughout the greater portion of its length to permit the free passage of said lugs as the forward section of the spring casing slides back and forth. Within the 15 spring housing a coiled spring 13 is seated, said spring being of sufficient length to maintain the plunger in abutment with the forward end of the air chamber when the 20 mechanism of the air gun is in discharged position.

Immediately beneath the companion sears a releasing hammer 16 is provided. Said 25 releasing hammer is pivoted at its forward end to the casing and is normally held in contact with the bottom plate 15 of the companion sears by means of a coiled spring 44 pressing against the under side thereof and resting within a recess in the casing. Pivotally mounted on the casing, immediately 30 behind the rearward portion of the hammer, a trigger 22 is provided, the lower end of said trigger extending down within the trigger guard 2 heretofore referred to. A 35 spring 23, seated within a recess provided in the stock, is adapted to bear against the rearward face of said trigger and maintain the same normally projected against a screw-threaded pin 24 adjustably mounted 40 within the trigger guard and serving as a limiting stop for the trigger.

The mechanism for setting the spring and at the same time moving the air chamber to a rearward position so that the gun may be 45 easily loaded through the opening 8 in the forward upper side of the casing, comprises a pair of levers 26, 27. The lever 27 is of U-shaped cross section, open on its upper side, and is pivoted at its rearward end to 50 a pin 28 mounted on the under side of the casing adjacent its rearward end. The lever 26 comprises a link pivotally connected to the lever 27 at one end and adapted to be received between the sides thereof. Said 55 link, adjacent its forward end, is off-set at a slight upward angle and is pivotally connected with the extension arm 25 mounted on the forward end of the air chamber. The forward end of the lever 27 may be provided 60 with a roughened terminal portion 29 so that the same may be easily grasped by the fingers of the user of the air gun.

As is clearly shown in Fig. 3 of the drawing, the casing 3 on its under side is slotted 65 for the greater portion of its length to re-

ceive the automatic hammer setting and locking slide 51 shown in detail in Figs. 5, 6 and 7. The edges of the slide are preferably provided with grooves adapted to engage with tongues formed on the edges of 70 the slot on the under side of the casing. The locking slide is provided at its rearward end with a locking plate 50 of greater thickness than the remaining portion of the slide and throughout its body portion is provided with a slot 52, the forward end of said slot being closed by a cross bar 53. Within the slot the lug 54 formed on the cylindrical air chamber 9 is adapted to be received.

As will be readily understood from Figs. 90 9, 10 and 11, the co-operation of the thickened locking plate 50 of the slide 51 with the hammer 16, and the lug 54 with the ends 95 of the slot 53 of the slide, bring about the automatic setting of the hammer and the maintaining of the same in inoperative position during the process of tensioning the main spring through the spring setting levers. Thus, as more particularly shown in Fig. 9, when the spring setting levers are moved to their rearward limit of motion the forward end of the air chamber will be 100 pressed against the plunger and force the same rearwardly until each lug 18 rides over the nose of its sear 14 and is locked against forward motion by passing behind the shoulder of the hooked portion 17 of said sears. At the same time the locking plate 105 of the slide presses against the upper face of the hammer and forces the rearward end thereof downwardly until it engages beneath the nose of the trigger. Through the lost motion connection provided by the slot 52 the locking plate remains above the body of the hammer until the levers reach a position shown in Fig. 10. Throughout the entire range of motion of the levers from the position shown in Fig. 9 to that shown in Fig. 10, the thickened locking plate remains 110 above the hammer and prevents accidental release thereof against the bottom plate of the companion sears. Thus, while the slide 115 able air chamber is moved rearwardly to give access to the recess within the rearward end of the barrel, there is no danger of the plunger being accidentally released and injuring the fingers of the user of the air gun while a bullet or other missile is being placed within the recessed portion of the bore.

When the levers are moved to the position shown in Fig. 10 and the opening 8 is almost entirely closed by the return of the air chamber 9 toward its normal position, the lug 54 is brought against the cross bar 53 of the slide and the continued motion of the lever 27 toward its normal position against the under side of the barrel and casing serves to move the slide forwardly and withdraw its locking plate 50 from 120 125 130

locking position above the hammer. Thus, when the spring setting lever is fully restored to its original position the rearward movement of the trigger will release the hammer so that it may strike the bottom plate of the sears and retract the forward hooked portion thereof from engagement with the lugs 18 on the forward section of the spring housing and permit the spring 10 to move the plunger forwardly through the air chamber compressing the air therein and discharging the bullet through the bore of the air gun.

Other modes of applying the principle 15 of my invention may be employed instead of the one explained, change being made as regards the mechanism herein disclosed, provided the means stated by any of the following claims or the equivalent of such 20 stated means be employed.

I therefore particularly point out and distinctly claim as my invention:—

1. In an article of the character described, the combination of a casing, a barrel connected with the forward end of said casing, an air chamber slidably longitudinally within said casing, a spring pressed plunger engaged within said air chamber, means associated with said air chamber for moving the same rearwardly in said casing and compressing the spring abutting said plunger, means for retaining said plunger in its rearward position, and automatic means for preventing the release of said plunger until said air chamber has been restored to substantially its normal position against the rearward end of said barrel.

2. In an article of the character described, the combination of a casing, a barrel connected with the forward end of said casing, an opening in the forward end of said casing giving access to the rearward end of said barrel, an air chamber slidably longitudinally within said casing and adapted to serve as a closure for said opening, a spring pressed plunger engaged within said air chamber, means associated with said air chamber for moving the same rearwardly in said casing and compressing the spring

abutting said plunger, means for retaining 50 said plunger in its rearward position, and automatic means for preventing the release of said plunger until said air chamber has been restored to substantially its normal position with access to the barrel through said 55 opening obstructed by said plunger.

3. In an article of the character described, the combination of a casing, a barrel connected with the forward end of said casing, an air chamber slidably longitudinally within 60 said casing, an extension arm projecting forwardly from said air chamber, a spring pressed plunger engaged within said air chamber, toggle mechanism engaged with the extension arm on said air chamber for 65 moving said air chamber rearwardly and placing said spring under tension, means for retaining said plunger in its rearward position, a slidable locking plate on the under side of said casing, and means associating 70 said air chamber with said locking plate for automatically preventing the release of said plunger until said air chamber has been restored to substantially its normal position 75 against the rearward end of said barrel.

4. In an article of the character described, the combination of a casing, a barrel connected with the forward end of said casing, an air chamber slidably longitudinally within 80 said casing, an extension arm projecting forwardly from said air chamber, a spring pressed plunger engaged within said air chamber, toggle mechanism engaged with the extension arm on said air chamber for 85 moving said air chamber rearwardly and placing said spring under tension, means for retaining said plunger in its rearward position, a slidable locking plate on the under side of said casing, and means associating 90 said air chamber with said locking plate for automatically preventing the release of said plunger until said toggle levers have been restored to substantially their normal position.

Signed by me, this 21st day of April, 95
1924.

EDGAR P. COOK.
